MOP HOLDER

Lambert Reiter, Minneapolis, Minn.

Application March 1, 1943, Serial No. 477,576

1 Claim. (Cl. 248—341)

My invention relates to improvements in mop holders and has for an object thereof to provide a simple, durable and inexpensive device of such character to and from which a mop may be easily applied and removed.

Another object of the invention is to supply a mop holder adapted readily to receive a mop and to hold the same with the free portion of the depending swab suspended within a bucket resting on the floor, whereby water from the swab may drip into the bucket and the swab will dry out smoothly and evenly.

A further object of the invention is to provide a mop holder of the instant nature that is pivotally suspended and swingable out of a vertical position, whereby the user may readily present the swab of the mop in a conveniently accessible position for the ready examination, trimming or other repair thereof.

Other objects of the invention resides in the novel combination and arrangement of parts and in the details of construction hereinafter illustrated and/or described.

In the accompanying drawing, Fig. 1 is a side elevational view of a mop hanger embodying one form of my invention, the same being shown as suspended from a supporting bracket issuing from a wall; Fig. 2 is a front elevational view of the form of hanger shown in Fig. 1, said hanger being illustrated as suspended from a ceiling; Fig. 3 is a perspective view in detail of a medial portion of the hanger, shown in Figs. 1 and 2, and illustrating, particularly, the handle-retaining member of said hanger.

Reference being had to the drawing, wherein similar reference characters are employed to designate similar parts throughout the several views, it will be seen that the illustrated form of my invention consists of a hanger A, constructed from a single length of wire, including a relatively long shank 10 having an attaching eye 11 at its upper end, a mop-supporting hook 12 at its lower end and a retaining eye 13 intermediate its ends.

The attaching eye 11 is adapted to be hingedly caught in an anchoring member such as an eye 14 secured to an elevated supporting bracket 15 on a wall 16 (Fig. 1), or secured to a ceiling 16 (Fig. 2). The axis of said eye 11 is at right angles to the shank 10 and admits of pivotal movement of said shank for purposes soon to appear.

The retaining eye 13, intermediate the ends of said shank 10, is laterally offset from the shank 10, the axis of said retaining eye being parallel with said shank and the inside diameter of said eye 13 being large enough to receive a mop handle, as at 17, whereby such handle may be readily threaded into said eye 13 from beneath the same.

The mop-supporting hook 12 turns upwardly beneath the retaining eye 13 and is adapted to catch in the head 18 of a mop. This hook is preferably disposed in relation to the floor 19, whereby the depending swab 20 of the supported mop will hang with the free end thereof within a bucket 21 on the floor. Thus, if a mop is hung in the holder A while wet, the water will drip from the swab 20 into the bucket 21 and 10 said swab will dry out smoothly and evenly.

Upon applying a mop to the holder A, the handle 17 of the mop is simply threaded upwardly through the retaining eye 13, the mop being thereafter lowered and the head 18 thereof 15 caught on the hook 12. When removing a mop from my holder, the operation is reversed, the mop being first lifted to disengage the head 18 thereof from said hook 12 and then lowered to withdraw the handle 17 from the retaining eye 13, thus wholly freeing the mop from the holder.

For the purpose of conveniently examining the mop swab 20 and trimming or otherwise attending thereto, the hanger may be swung into 25 a position such as that shown in dotted lines in Fig. 1 in which position and with the mop still supported by the hanger, the swab 20 is readily accessible to the user for such treatment as may be required.

Changes in the specific form of my invention, as herein disclosed, may be made within the scope of what is claimed without departing from the spirit of my invention.

Having described my invention, what I claim 30 as new and desire to protect by Letters Patent is:

A mop holder adapted to be pivotally suspended from a supporting member above a floor, said holder being formed from a single length of wire and comprising a shank longer than the 35 handle of a mop to be held and having an attaching eye at its upper end for permanent hinging cooperation with such supporting member, said shank having a hook at its lower end and having between its ends a laterally offset retaining eye 40 for the handle of the mop, the axis of said eye paralleling said shank, said eye being adapted freely threaded to receive the mop handle from beneath the same, said hook being upturned with its crotch disposed in the axis of said retaining eye, said hook being adapted to catch in the head of the mop beneath the mop handle and across the axis thereof to support the mop with its swab 45 depending in parallelism with the mop-handle and with the free end of said swab positioned to 50 hang within a bucket on the floor.

LAMBERT REITER.
